APPARATUS FOR CLEANING AIR AND
OTHER GASESWilly Neumann, Rollberg over Bernau, near
Berlin, GermanyApplication March 20, 1939, Serial No. 263,027
In Germany December 14, 1938

3 Claims.

(Cl. 183—8)

The present invention relates to an apparatus for cleaning air and other gases, in which a liquid bath for washing the dusty air is arranged to the path of the dusty air through the purifier. Air purifiers which use a liquid bath for washing the air are in themselves known. They work as follows:

The dust-containing air, impinging with relatively great velocity on the liquid, on its path through the purifier, sets this liquid into wave motion. By its impact on the liquid surface, the air loses a part of the dust carried therewith, and a further part is deposited by the air being compelled to flow through a rain of spray of the liquid formed by its impact on the liquid. Often the sprayed liquid is led further into a filter layer, through which the air flows, in order to obtain as intimate a contact as possible between air and liquid. Plainly, this intimate contact between the air to be purified and the washing liquid is to be striven for, since only in this way can high degrees of purification be obtained. The present invention is specially suitable for bringing about such an intimate contact in a high degree and with very simple means.

According to the invention a stationary leading or guiding member, formed of sheet metal, and consisting of vanes, which wholly or partially dips into the liquid or arranged immediately above the same, is inserted in the air path.

According to a further feature of the invention the guiding vanes are curved and so inserted in the leading or guiding member, that within this member, the flowing air receives a turning movement.

Further, the surfaces of the leading vanes can be so inclined towards the vertical that the air currents escaping from the guide member underneath receive a lead against that escaping above.

Different methods of carrying out the invention are illustrated diagrammatically in the accompanying drawing, in which:

Figure 1 shows a longitudinal section through the apparatus according to the invention with passage of the air to be purified in an upward direction.

Figure 2 shows a plan of the guide member, and

Figure 3 a part of the guide member in perspective view.

Figure 4 is a longitudinal section through another form of the apparatus according to the invention, in which the passage of the air takes place from above downwards.

Figure 5 is again a partial plan of the guide member.

Figure 6 is a partial longitudinal section through a further form of the apparatus according to the invention, and

Figure 7 is a perspective view of further guiding vanes.

The air to be purified is fed to the casing 1 through the conduit 2, which according to Figure 1, extends centrally into the casing 1 from below. In contrast thereto in Figures 4 and 6, the arrangement is so chosen that this introduction pipe 2 for the dusty air, extends centrally from above downwards into the casing 1.

Behind this introduction pipe 2 is positioned a stationary guide member 3, in the path of the dusty air. This has the function of so diverting the dusty air, fed into the apparatus in a vertical direction, that it flows out in a horizontal direction into the casing 1. The paths of flow of the air are shown in the drawing by arrows. The guide member 3 consists in all forms of construction of a plurality of guiding vanes or scoops which have the object of distributing the air as uniformly as possible over the whole circumference of 360° of the guide member outlet.

In the lower part of the casing 1, there is provided the liquid 5 serving to wash the dusty air.

It is preferably at such a level in the casing that the guide member as shown in Figures 1 and 4 dips partially into the liquid. However the arrangement can be so chosen that the liquid completely covers the guide member, or the liquid level can be immediately under the guide member

(see Figure 6) without the mode of working of the apparatus being substantially affected. In so far as the apparatus illustrated in Figure 6 is concerned, in which the liquid level lies below the guide member, it is advantageous to give the air in the guide member a direction inclined downwardly, as is shown in Figure 6. Obviously it is also possible to construct this apparatus so that the guide member 3 partially or wholly dips into the liquid.

The air flowing out of the guide member in all directions with relatively greater velocity, sets the liquid 5 into violent motion, so that the desired intimate contact between liquid and air occurs.

This mixing can be obtained to a still greater extent by so forming and inserting the blades or scoops 4 that the air on flowing through the guide member is given a strong rotary motion, as is obvious from Figures 2 and 5, also Figures 3 and 7. This motion is then communicated to the

liquid which also acquires a strong circulatory motion. It is thereby driven by the flowing air against the walls 6 of the casing 1 where it forms a film providing extensive contact with the air. In this manner there occurs an extraordinarily intimate contact between liquid and dust-containing air, which affords as a consequence a high degree of cleansing of the apparatus. The whirling motion however should not be so violent as to atomise the liquid into drops, because such are easily carried away by the air and would pass to the place of use of the cleaned air, where they are obviously undesirable.

According to Figure 3, the guide vanes are vertical, while according to Figure 7, they are so inclined to the vertical that the air currents escaping at the bottom from the guide member 3 obtain a lead as compared with those escaping at the top. This oblique position is more advantageous from a technical view point in the examples according to Figures 4 and 6, with air flowing in at the top than the vertical arrangement of the vanes or blades according to Figures 1 and 3. However there is nothing to prevent this oblique position of the vanes 4 also occurring in the example according to Figure 1 with air flowing in at the bottom.

The wall 6 of the casing 1 of the apparatus has approximately the form of half an ellipsoid of rotation. By this very favourable shape it is ensured that the liquid climbs to the upper edge 7 of the casing. The wall 6 is thus continuously covered inwardly from bottom to top, with a liquid layer, which is kept in steady motion by the flow of the air. By this layer the washed out dust particles or those centrifuged out by centrifugal force, are taken up and fixed. The upper edge 7 of the wall 6 is formed as a trap ring to limit the height of climb of the liquid to this point.

The thoroughly washed and cleaned air finally passes to a filter insert 8, in which it undergoes a subsequent purification. As filter medium for the insert can be used one of the known suitable materials for this purpose, such as perforated plates, fabrics, ring bodies etc. The examples according to Figures 1 and 4, show an insert 8 having the form of a conical frustum. It can of course, be formed in any other way, e. g. as a cylinder, or as illustrated in Figure 6, a disc. Between the filter insert 8 and the wall 6 of the casing 1 is further arranged a damping grating 9, which has the function of converting the circulatory motion of the air which has been given to it by the guide member into straight line motion again, and to keep the greater part of the liquid from the filter insert.

This damping grating 9 can consist of any permeable substance. Expanded metal has been found to be equally suitable therefor.

After passage through the filter insert 8 the air, now freed from all dust particles, flows into

the dead space 10, from which it passes into the pure air pipe 12 arranged in the cover hood 11, which pipe leads the air to the place of use.

The apparatus according to the invention can be used with special advantage where it is a question of freeing very impure air from suspended particles, for example, for the cleaning of air drawn from grinding machines, the cleaning of the air of combustion for internal combustion engines, the cleaning of the air feed to compressors and other air consuming machines etc.

I claim as my invention:

1. Apparatus for purifying air and other gases, comprising a housing, a liquid bath in said housing, upper and lower guide members in said housing arranged to impart a substantially horizontal direction of flow to the entire air to be purified, said guide members being substantially parallel to each other and the lower of said members being in the form of a closed bottom, and a plurality of vanes arranged between said guide members to impart a rotating direction of flow to the air passing between said guide members, said vanes being essentially greater in diameter than the distance of said guide members from each other and the walls of said housing being curved and enlarged at least in the region of and above said guide members and above said liquid bath, said vanes extending almost to said curved and enlarged walls.

2. Apparatus for purifying air and other gases, comprising a housing, a liquid bath in said housing, upper and lower guide members arranged to impart a substantially horizontal direction of flow to the air to be purified, said guide members being substantially parallel to each other and to the surface of said liquid bath and the lower of said members being in the form of a closed bottom, and a plurality of vanes arranged between said guide members to impart a rotating direction of flow to the air passing between said guide members, the walls of said housing being curved at least in the region of and above said guide members and said vanes extending almost to said curved walls.

3. Apparatus for purifying air and other gases, comprising a housing with curved walls, a liquid bath in said housing, upper and lower guide members arranged to impart a substantially horizontal direction of flow to the air to be purified, said guide members being substantially parallel to each other and to the surface of said liquid bath, and the lower of said members being in the form of a closed bottom, a plurality of vanes arranged between said guide members to impart a rotating direction of flow to the air passing between said guide members, said curved housing walls extending almost to said vanes, and a damping grating in the form of a truncated cone and extending from the outlet of said vanes along the upper portion of the housing walls.

WILLY NEUMANN.
